EVAPORATIVE COOLING SYSTEM

Everett B. Eyleth, Bryn Mawr, Pa., assignor to
Minneapolis-Honeywell Regulator Company,
Minneapolis, Minn., a corporation of Delaware

Application March 23, 1938, Serial No. 197,689

13 Claims. (Cl. 236—44)

This invention relates to an air conditioning system and more particularly to a cooling system wherein the cooling of the air is effected by means of evaporating moisture therein.

5 In many sections of the country having low relative humidity during the greater portion of the cooling season it has been found that the cooling of the air within a space may be effectively attained by means of spraying water into 10 a stream of air drawn into the space from outdoors. Since the incoming air will usually have a low relative humidity, the cooling of the air may be effected without raising the humidity to 15 an undesirable value. It sometimes happens however that even in these sections of the country wherein such systems are found useful that the air being drawn in from outdoors will have such a high relative humidity that the cooling of the air by evaporating moisture therein will 20 produce uncomfortable conditions in the space and will be undesirable.

One of the objects of my invention is to provide a novel control system for an evaporative cooling system wherein means are provided to 25 prevent the operation of the cooling system when the humidity within the space becomes excessive.

Other objects will become apparent upon a 30 study of the specification, claims, and appended drawing in which is illustrated a preferred form of my invention.

Referring more particularly to the drawing, a 35 cooling chamber 10 having a fresh air inlet 11 and an outlet 12 may be positioned near the upper portion of the space which is to be cooled. Mounted within the chamber 10 is a fan 14 for drawing air into the chamber 10 through the inlet 11 and exhausting the air from the exit 12. A motor 15 is provided for causing the 40 operation of the fan 14 and may be controlled in any suitable manner, not illustrated.

Located adjacent the inlet 11 of the chamber 10 is a filter 18 through which all the air entering the chamber 10 passes. A spray 20 is mounted in the chamber downstream from the filter 18 and a valve 21 controls the flow of water to the spray 20. Mounted just downstream from the spray 20 is a set of eliminator plates 22 of any suitable well known construction for removing 45 particles of moisture from the air, there being a sump 23 located beneath the plates 22 and provided with an outlet 24 through which the water drains. Mounted near the outlet 12 is a set of dampers 25 connected by means of links 26, 27, 50 and 28 to an arm 29 operated by a motor 30 as

will be described. Also connected to the links 27 and 28 is a damper 32 suitably pivoted at 33, this damper being provided for suitably directing the air passing through the chamber 10 downwardly when cooling is desired within the space. 5

Suitably mounted within the space being cooled is a thermostat 35, this thermostat including a bimetallic element 36 carrying an arm 37 which is caused to move by the bimetallic element 36 in response to temperature changes within the 10 space being cooled. Fixed contacts 38 and 39 cooperate with the arm 37, the arm 37 moving toward the left and into engagement with the contact 38 in response to a temperature drop within the space and moving towards the right 15 into engagement with the contact 39 in response to a temperature rise within the space.

Also mounted within the space being cooled is a humidity responsive device 40, which device may include an element 41 which expands or 20 contracts in response to varying humidities within the space. The upper portion of the element 41 is suitably fixed and the lower portion of this element is connected to an arm 42 pivoted at 43, the arm 42 being biased in a direction to cause elongation of the element 41 by means of a spring 45. Fixed contacts 46 and 47 cooperate with the right end of the arm 42 which is suitably insulated by means of insulating material 48 from the rest of the arm. When 30 the humidity within the space rises the humidity responsive element 41 elongates and permits the right end of arm 42 to move into engagement with the contact 47 under the influence of the biasing spring 45. Upon a drop in humidity within the space, the element 41 contracts and causes the right end of arm 42 to move upwardly and into engagement with the contact 46. 35

The motor 30 causing operation of arm 29 may be a reversible two-position motor of any 40 suitable construction and may include a pair of selectively energized windings, one of these windings being energized upon connection of terminals 50 and 51 and the other winding being energized upon connection of terminals 51 and 45 52. Power may be supplied to the motor 30 by means of conductors 53 and 54 which may be connected to a suitable source of power, not shown. When terminals 50 and 51 are connected together, the motor operates to rotate arm 29 to the position in which it is illustrated in the drawing. When terminals 51 and 52 are connected together, the motor operates to rotate the arm 29 in a clockwise direction to a position wherein the dampers 25 are moved to a posi- 50

tion wherein the volume of air flowing thereby is reduced to a minimum and the damper 32 is simultaneously moved upwardly so that the air leaving the chamber will not be directed downwardly.

Mounted on the left end of the arm 29 is a mercury switch 56 which includes a mercury element 57 and terminals 58, 59, 60, and 61. This switch controls the operation of a motor 65 for controlling the position of the valve 21 in a manner to be set forth. This motor may be similar in construction to the motor 30 and may include a winding energized upon connection of terminals 66 and 67, which causes the valve 21 to be moved to open position whereupon water is sprayed from the spray 20. A second winding energized upon connection of the terminals 67 and 68 causes the motor 65 to move the valve 21 to closed position when energized.

20   Operation

With the parts in the position illustrated, the temperature within the space to be cooled is relatively high whereas the humidity is not excessive. The terminals 50 and 51 are connected together through the following circuit: from the terminal 50 through conductor 70, contact 39, the arm 37 of thermostat 35 and conductor 71 to the terminal 51. The motor 30 has accordingly operated to move the arm 29 to the position shown, thus moving the dampers 25 to their wide open position and the damper 32 to the position wherein the air is deflected downwardly. The terminals 58 and 59 of the mercury switch 56 are connected together and accordingly the terminals 66 and 67 of the motor 65 are connected together so that the valve 21 is in open position, through the following circuit: from terminal 66 through conductor 75, the terminal 58 of switch 56, mercury element 57, terminal 59, conductor 76, contact 46, the right end of arm 42 of the humidity responsive device 40, and conductor 78 to the terminal 67 of motor 65. Water accordingly flows through the spray 20 thus effecting cooling of the air flowing through the chamber 10 by means of evaporation.

45   When the temperature within the space drops to a desired value, the arm 37 of thermostat 35 moves into engagement with contact 38 thus connecting the terminals 51 and 52 of motor 30 as follows: from terminal 52 through conductor 80, contact 38, arm 37, and conductor 71 to the terminal 51. Motor 30 now operates to rotate the arm 29 in a clockwise direction thus moving the dampers 25 to minimum open position and moving damper 32 upwardly, at the same time tilting the mercury switch 56 in the opposite direction wherein terminals 60 and 61 are connected together by the mercury element 57. Terminals 67 and 68 of motor 65 are now connected together as follows: from terminal 68 through conductors 82, 83, terminals 61 and 60 of switch 56, conductor 76, contact 46, arm 42, and conductor 78 to the motor terminal 67. Motor 65 now operates to close the valve 21 thus stopping the flow of water to the spray 20 so that the air passing through the chamber 10 is no longer being cooled. The spray 20 will remain shut off and the dampers 25 will remain closed until the temperature within the space again rises to a value wherein the arm 37 engages the contact 39.

70   Assuming now that the parts are in the position illustrated wherein the thermostat 35 is calling for cooling, the spray 20 is turned on, the dampers 25 are open, and damper 32 is deflecting the air downwardly into the space. Should the 75 humidity within the space become excessive, the

humidity responsive element 41 will expand and permit the right end of arm 42 to move into engagement with the contact 47. This will cause the terminals 67 and 68 of motor 65 to be connected as follows: from terminal 68 through conductors 82, 85, contact 47, arm 42, and conductor 78 to the terminal 67 whereupon the motor 65 will operate to close the valve 21 and prevent further supply of water to the air passing through the chamber 11. This circuit is independent of the mercury switch 56 and it will therefore be seen that as long as the humidity within the space remains excessive that the valve 21 will remain closed regardless of temperature conditions within the space.

15   The system provides for a minimum supply of air to the space at all times for ventilation purposes and for a maximum supply of air to the space when cooling is required.

It will now be seen that I have provided a 20 novel control system for an evaporative cooling system wherein the operation of the spray for supplying water to the air which is to be cooled by evaporation is normally under the control of a temperature responsive device so that water is 25 supplied to the air only when the temperature therein becomes excessive, and wherein a humidity responsive device prevents the supply of water to the space whenever the humidity therein becomes excessive regardless of the temperature 30 existing therein.

Having described a preferred form of my invention many modifications may become apparent to those skilled in the art and I wish it to be understood that my invention is limited only by the scope of the appended claims.

I claim as my invention:

1. In an evaporative cooling system, means for spraying water into the air to be cooled whereby the evaporation of the water causes a reduction 40 in the temperature of the air being cooled, temperature responsive means for causing operation of the spraying means when the temperature of the air being cooled rises above a predetermined value and to interrupt said spray when the temperature drops below a predetermined value, and 45 humidity responsive means also in control of the spraying means to interrupt operation thereof when the humidity of the air being cooled rises above a predetermined value.

2. In an evaporative cooling system, means for spraying water into the air to be cooled whereby the evaporation of the water causes a reduction in the temperature of the air being cooled, valve means controlling the flow of water to the spraying means, means responsive to the temperature of the air being cooled in control of said valve means whereby water flows to said spraying means only when the temperature of the air being cooled is above a predetermined value, and 60 means responsive to the humidity of the air being cooled also in control of said valve means whereby the valve means prevents the flow of water to the spraying means whenever the humidity of the air being cooled exceeds a predetermined 65 value regardless of the temperature in said space.

3. In a cooling system, a cooling chamber including a fresh air inlet and an outlet opening into a space to be cooled, volume damper means in control of said outlet, means for drawing air 70 into said chamber through said inlet and exhausting said air through said outlet, means within said chamber for spraying water into the air passing through said chamber whereby the evaporation of the water causes a reduction in 75

the air temperature, means responsive to the temperature of the space being cooled for causing movement of the damper means towards open position and for causing operation of the spraying means when the space temperature reaches a predetermined value, and means responsive to the humidity in the space being cooled for preventing operation of the spraying means whenever the humidity in the space exceeds a predetermined value regardless of the temperature in the space.

4. In a cooling system, a cooling chamber including a fresh air inlet and an outlet opening into a space to be cooled, volume damper means in control of said outlet, means for drawing air into said chamber through said inlet and exhausting said air through said outlet, means within said chamber for spraying water into the air passing through said chamber whereby the evaporation of the water causes a reduction in the air temperature, valve means in control of said spraying means, temperature responsive means in control of said valve means and damper means whereby the damper means are opened 25 and the valve means is opened to cause operation of the spraying means when the space temperature rises to a predetermined value, and humidity responsive means also in control of said valve means to prevent flow of water to the spraying means whenever the humidity in the space reaches a predetermined value.

5. In a cooling system, means for spraying water in the space to be cooled whereby the evaporation of the water causes a reduction in the temperature of the air in said space, and means responsive to the temperature and humidity in said space for causing operation of the spraying means only when the temperature in the space is above a predetermined value and the humidity 35 in the space is below a predetermined value.

6. In a cooling system, means for causing a flow of outdoor air into a space to be cooled, means for spraying water into said air flow whereby the evaporation of the water causes a reduction in the temperature of the air in said space, and means responsive to the temperature and humidity in said space for causing operation of the spraying means only when the temperature in the space is above a predetermined value and the humidity 45 in the space is below a predetermined value.

7. In a cooling system, means for causing a flow of outdoor air into a space to be cooled, means for spraying water into said air flow whereby the evaporation of the water causes a reduction in the temperature of the air in said space, means responsive to the temperature and humidity in said space for causing operation of the spraying means only when the temperature in the space is above a predetermined value and the humidity in the space is below a predetermined value, and means responsive to the temperature of the air in the space for controlling the rate of flow of the air into the space.

8. In a cooling system, means for causing a flow of outdoor air into a space to be cooled, means for spraying water into said air flow whereby the evaporation of the water causes a reduction in the temperature of the air in said space, means responsive to the temperature and humidity in said space for causing operation of the spraying means only when the temperature in the space is above a predetermined value and the humidity in the space is below a predetermined value, and means responsive to the tem-

perature of the air in the space for controlling the rate and direction of the air flow into the space.

9. In a cooling system, a cooling chamber including a fresh air inlet and an outlet opening 5 into a space to be cooled, volume damper means in control of said outlet, means for drawing air into said chamber through said inlet and exhausting said air through said outlet, means within said chamber for spraying water into the air passing through said chamber whereby the evaporation of the water causes a reduction in the air temperature, means responsive to the temperature of the space being cooled for causing movement of the damper means to open position and for causing operation of the spraying means when the space temperature exceeds a predetermined value, means responsive to the humidity in the space being cooled for preventing operation of the spraying means whenever the 10 humidity in the space exceeds a predetermined value regardless of the temperature in the space, and means for causing the air leaving said chamber to be directed downwardly as the volume of the air leaving said chamber increases. 15

10. In an evaporative cooling system, a cooling chamber, means for circulating fresh air through said chamber and a space to be cooled, damper means controlling the flow of air through the chamber, means for controlling the position 30 of said damper means, means responsive to the temperature of the space being cooled in control of said position controlling means whereby the damper means are in open position when the temperature in the space is above a predetermined value and are moved toward closed position when the temperature in the space is below a predetermined value, means for spraying water into the cooling chamber, valve means in control of said spraying means, and means for 35 moving the valve means to open position only when the damper means are in open position and the humidity in the space is below a predetermined value.

11. In an evaporative cooling system, a cooling 45 chamber, means for circulating fresh air through said chamber and a space to be cooled, damper means controlling the flow of air through the chamber, means for controlling the position of said damper means, means responsive to the 50 temperature of the space being cooled in control of said position controlling means whereby the damper means are in open position when the temperature in the space is above a predetermined value and are moved toward closed position when the temperature in the space is below a predetermined value, a control device operated by the position controlling means for the damper means, means for spraying water into the cooling chamber, valve means in control of said spraying means, means responsive to the humidity in the space being cooled, and means controlled by the control device and the humidity responsive means for controlling said valve means for causing the opening of said valve means only when the humidity in the space is below a predetermined value and the damper means are in open position.

12. In an evaporative cooling system, a cooling 70 chamber, means for circulating fresh air through said chamber and a space to be cooled, damper means controlling the flow of air through said chamber, a motor for controlling the position of said damper means, means responsive to the temperature of the air in said space in control of

- 5 said motor, means for spraying water into the air passing through said chamber, valve means in control of said spraying means, a switch operated by said motor having a first circuit controlling position when the damper means are in open position and having a second circuit controlling position when the damper means are moved towards closed position, a motor in control of said valve means, means responsive to the 10 humidity of the space being cooled, circuit connections for causing said second motor to move the valve means to closed position when said switch is in the second circuit controlling position, and circuit connections controlled by said 15 humidity responsive means for causing said second motor to move the valve means to open position only when the humidity in the space is below a predetermined value and said switch is in the first circuit controlling position.
- 20 13. In an evaporative cooling system, spray means for reducing the temperature of the air in a space by evaporation of water, valve means

controlling the operation of said spray means, electrical means in control of said valve means, means responsive to the humidity of the space, said humidity responsive means including switching means movable to a first position in response to a low relative humidity in the space and movable to a second position in response to a high relative humidity in the space, means responsive to the temperature of the space, said temperature responsive means including switching means movable to a first position in response to a high temperature in the space and movable to a second position in response to a low temperature in the space, circuit connections controlling said electrical means, said circuit connections including said switching means and means operative when both switching means are in the first positions to cause the electrical means to open the valve and operative when either of the switching means is in the second position to cause the electrical means to close the valve. 15 20
